[57] CLAIM

The ornamental design for a hoop roller, as shown and described.

DESCRIPTION

FIG. 1 is a front elevational view of a hoop roller showing my new design;

FIG. 2 is a rear elevational view thereof;

FIG. 3 is a side elevational view thereof;

FIG. 4 is a top plan view thereof;

FIG. 5 is a bottom plan view thereof; and,

FIG. 6 is a side elevational view of the side opposite that shown in FIG. 3 with the handle member in an alternate position.
